ANTON J. HAUG, OF NASHUA, NEW HAMPSHIRE, ASSIGNOR TO IMPROVED PAPER MACHINERY COMPANY, OF NASHUA, NEW HAMPSHIRE, A CORPORATION OF MAINE.

PAPER-STOCK-SCREENING MACHINE.

1,183,297.

Specification of Letters Patent. Patented May 16, 1916.

Application filed November 7, 1913. Serial No. 799,750.

To all whom it may concern:

Be it known that I, ANTON J. HAUG, a citizen of Germany, residing at Nashua, in the county of Hillsborough and State of 5 New Hampshire, have invented certain new and useful Improvements in Paper-Stock- Screening Machines, of which the following is a specification.

This invention relates to paper making 10 machines and particularly to machines for removing the knots and slivers from ground wood and chemical pulp in the processes of paper making. Its purpose is to separate the fine or good stock from the slivers, 15 shives or so-called knots. It is in fact a pulp screen.

My purpose is to provide a machine which will have a continuous feed, continuous delivery of the screened stock and continuous 20 discharge of the knots and one which will rapidly carry the knots away from the other stock so that they will not form a filter or bed and so clog the operation.

My pulp screen is especially valuable for 25 use in the first screening or knotting process wherein the large knots and other large pieces in the pulp are separated. It may be used to advantage, however, not only for the first knot screening but for the second or 30 coarse screening, and for the third or fine screening. The only change necessary in these different processes is the substitution of smaller perforations in the screening plates for the larger ones, the use of narrower slots or finer screening.

In the drawings, Figure 1 shows a sectional side elevation of the preferred form of the machine. Fig. 2 shows a sectional end elevation on the line X—Y of Fig. 1 40 looking toward the left. Fig. 3 is a detail of the shaking action. Fig. 4 shows a sectional side elevation of a modification of the device with the drying cylinder removed. Fig. 5 shows a sectional end elevation of 45 another modification of the device being a view similar to Fig. 2. Fig. 6 is a partial sectional side elevation of Fig. 5 as viewed from the left of line S—T. Fig. 7 shows a modified form of perforated plate.

50 A is the tank into which the screened stock is delivered. 21 is the outlet therefrom.

H is a separating cylinder which is shown in Figs. 1, 2 and 4 as being polygonal. The

outside faces 10 of this separating cylinder 55 are formed of screens or preferably of sheets of perforated metal and as shown in Fig. 2 the ends are partly covered preferably by similar screens or preferably perforated plates 11 and 12. As shown in Fig. 60 2, these end screens or plates 11 and 12 extend inward to about the same distance whereby there is a polygonal opening of considerable size at each end of the cylinder. Radial partitions 13 are also provided and these are preferably formed of perforated plates or screens similar to those on the outside face and ends. They extend inward to about the same point as the inward ends of plates 11 and 12. It will thus 65 be seen that adjoining the outer face of separating cylinder B on the inner side thereof are formed a plurality of longitudinal pockets L which are open toward the center or axis of the cylinder and are 70 preferably formed of perforated plates on all other sides. Cylinder B is supported on driving shaft C by means of a spider 16 which is fixed to shaft C and to the arms of which one end of cylinder B is firmly 75 bolted. As the cylinder B is thus supported only at one end, I prefer to stiffen the other end by bolting thereon a disk 17. Spider 16 also supports one end of drying cylinder K as will be hereafter explained. Shaft C 80 and cylinder B are so placed that as the cylinder revolves, the lower portion preferably extends below the surface of the liquid in tank A.

It is not necessary that cylinder B should 90 extend below the surface of the liquid in tank A but I find that better results are obtained by so doing as the movement of the cylinder through the liquid and the passage of the liquid through the perforated plates 95 agitates the stock and prevents the formation of any filters or beds to clog the action. Extending into the central opening of cylinder B is the inlet pipe or conveyer F which conveys the unscreened stock inside 100 thereof. It will thus be seen that the unscreened stock G is delivered into the sections or pockets L of cylinder B as they pass a certain point relative thereto.

I prefer to make the discharge end 20 of 105 inlet pipe F at the side as shown in Fig. 2 so that as the unscreened stock is discharged into the pockets, its weight will help to

revolve cylinder B in the direction of the arrow as shown. As the unscreened stock passes into the pockets L, the finer part thereof passes through the perforated plates 5 into tank A while the knots, slivers and other undesirable material is carried along in the pocket until it reaches a point near the top as the cylinder revolves when, as shown in Figs. 1 and 2 at 30, it slides off 10 toward the axis of the cylinder and is received by a trough H which slopes downward in a direction away from the inlet pipe F. Attached to spider 16 and extending therefrom into separating cylinder B in 15 such a position that its smaller end extends under and beyond the end of trough H is a delivery cone 70, which conducts the stock from trough H into drying cylinder K.

I prefer to deliver the knots and slivers 20 as shown in Fig. 1 to a drying cylinder K which is carried by the same spider or support 16 which carries separating cylinder B and is also supported at its other end by a disk 37 as shown. This drying cylinder K 25 may be of any regular design in cross section but it should be in the form of a truncated cone or pyramid with walls which slope at the bottom from where they adjoin cylinder B downward toward the other end 30 so that the knots 30 will travel along and be finally delivered through openings into a discharge outlet 41. From knot outlet 41, the knots may be removed in any desired 35 way as by a belt conveyer. Drying cylinder K preferably is made with a longitudinal skeleton frame work 18 which extends between spider 16 and disk 37 and is connected by perforated plates 19 which extend close to spider 16 and to within a short distance 40 of disk 37 so that the knots 30 can be delivered through the opening between their ends and disk 37 into the knot outlet 41. The knots 30 are carried around by drying cylinder K and the moisture is dried out 45 and whatever liquid there is escapes and falls into tank A.

To prevent the clogging of the holes in the perforated plates, to accelerate the process of separation and also to help the continuous feed and the delivery of the knots, I prefer to give the driving or supporting shaft C a reciprocating motion by any suitable means. This shaft is preferably driven by a pulley 38 and preferably at the other 50 end I fix an end cam 42 and a compression spring 44 which tends to force shaft C, pulley 38 and cylinders K and B toward the left. In engagement with end cam 42, I may use one or more rollers 43 fixed to the 55 shaft bearing 50 in engagement with end cam 42 so that while shaft C is revolving, it is moved gently back and forth in its bearings 50 and 51.

As shown in Fig. 4, I may dispense with 60 the drying cylinder K and deliver the knots,

slivers and other undesirable material directly into a trough or chute 60 along which they pass until they fall on to a cone 61, from whence they drop into a knot outlet 41.

In Fig. 4, I show woven wire screens 90 which are substituted throughout for the perforated plates. I also show the driving pulley omitted, as such a pulley is not necessary with my device on account of the 70 fact that the arrangement of the inlet pipe and the delivery end thereof is such that it will cause the separating cylinder to revolve without outside power. I prefer to use a driving shaft, however, so that the 75 speed may be equalized and so that there may be no possibility of the device becoming clogged and overflowing.

Also as shown in Figs. 5 and 6, I may use 80 a separating cylinder M which is cylindrical on its outer face which is formed of 85 perforated plates 104. In this construction the end plates 101, 102 and partition plates 103 are imperforate, only the outside plates 104 being perforated. This makes the 90 pockets imperforate except on the outside and thus adds to the propelling power of the stock from the inlet pipe acting thereon. I also show in Figs. 5 and 6, the delivery 95 end 20 of the inlet pipe at a point higher up than in Figs. 1 and 2 whereby also greater power is obtained.

In Fig. 7, I show a fragment of a plate 106 provided with slots 107 thereby forming a sort of grate which can be substituted 100 for the perforated plates or woven wire screens if desired. In fact any means such as parallel bars may be used to hold back the coarse stock and to allow the fine stock to drain off. I prefer to have the perforations or meshes in the drying cylinder finer 105 than those in the separating cylinder so that any knots or other large pieces which may be broken up or reduced in size in traveling around the two cylinders cannot fall 110 through into the tank A.

The shaft C is a supporting shaft for the separating cylinder or for the separating cylinder and drying cylinder and is a driving shaft only when it carries a driving pulley, or it may be considered as a driving shaft which supports both cylinders and transmits power from the separating cylinder to the drying cylinder when a driving pulley is not used. In either case, this 115 supporting shaft should be slideable longitudinally in its bearings to permit of the shaking or reciprocating action described.

I prefer to use in connection with my 120 paper stock screening machine, a shower pipe R which extends over the top of the separating and drying cylinders and delivers clean water upon both, thereby washing the fibers from the knots and washing the screens and the machine.

I claim:

1. In a paper stock screening machine, the combination of a foraminous separating cylinder having a plurality of interior pockets open toward the inside, with a stock inlet pipe which enters the cylinder, a trough which slopes downward inside the cylinder, and a driving shaft which carries the separating cylinder, together with a tank below the cylinder substantially as described.

2. In a paper stock screening machine, the combination of a foraminous separating cylinder, having a plurality of interior pockets open toward the inside, with a stock inlet pipe which enters the cylinder in such a manner as to discharge into the pockets, a drying cylinder which adjoins the separating cylinder, and a driving shaft which carries the separating cylinder and the drying cylinder, together with a trough which slopes downward inside the separating cylinder to a point adjoining the drying cylinder, and a tank below the separating cylinder substantially as described.

3. In a paper stock screening machine, the combination of a foraminous separating cylinder, having a plurality of interior pockets open toward the inside, with a stock inlet pipe which enters the cylinder in such a manner as to discharge into the pockets, a drying cylinder which adjoins the separating cylinder, and a driving shaft which carries the separating cylinder and the drying cylinder, together with a trough which slopes downward inside the separating cylinder to a point adjoining the drying cylinder, and a cone which extends from the drying cylinder into the separating cylinder in operative relation with the trough.

4. In a paper stock screening machine, the combination of a foraminous separating cylinder, having perforated end plates which partly close its ends, and perforated partition plates between such end plates forming a plurality of perforated interior pockets open toward the inside, with a stock inlet pipe which enters the cylinder, a trough which slopes downward inside the cylinder, and a driving shaft which carries the separating cylinder, together with a tank below said cylinder substantially as described.

5. In a paper stock screening machine, the combination of a foraminous separating cylinder having a plurality of interior pockets open toward the inside, with a stock inlet pipe which enters the cylinder, a trough which slopes downward inside the cylinder, driving shaft bearings, and a driving shaft slidably in said bearings and which carries the separating cylinder, together with a tank below said cylinder, and means for moving the shaft back and forth in its bearings substantially as described.

6. In a paper stock screening machine, the combination of a supporting shaft, with

a foraminous separating cylinder carried thereby, having a plurality of interior pockets open toward the inside, a stock inlet pipe which enters the cylinder at such a point as to discharge into the pockets on the inside between the top and bottom of the cylinder, a trough which slopes downward inside of and lengthwise of the cylinder, and a tank below the cylinder substantially as described.

7. In a paper stock screening machine, the combination of a supporting shaft, with a separating cylinder having a plurality of interior pockets which open toward the inside all the sides of said pockets being perforate, a stock inlet pipe which enters the cylinder at such a point as to discharge into the pockets on the inside between the top and bottom of the cylinder, a longitudinal trough which slopes downward inside the cylinder, together with a tank below said cylinder substantially as described.

8. In a paper stock screening machine, the combination of a separating cylinder having a plurality of interior pockets with perforate walls and open toward the inside, with a driving shaft which carries the separating cylinder, a drying cylinder also carried thereby, a stock inlet pipe which enters the separating cylinder, a cone which extends from the drying cylinder into the separating cylinder, a longitudinal trough which slopes downward inside the separating cylinder to a point inside the cone, together with a tank below said cylinder substantially as described.

9. In a paper stock screening machine, the combination of shaft bearings, a supporting shaft slidable in said bearings, and a foraminous separating cylinder carried thereby having a plurality of interior pockets open toward the supporting shaft, with a stock inlet pipe which enters the cylinder at such a point as to discharge into the pockets on the inside between the top and bottom of the cylinder, a trough which slopes downward inside of and lengthwise of the cylinder, a tank below the cylinder, and means for moving the shaft and cylinder back and forth in its bearings substantially as described.

10. In a screening machine, a rotatable, foraminous screening drum having interior blades and means to deliver stock to said blades along a line at one side of and radially removed from the axis of the drum.

11. In a screening machine, a rotatable, foraminous screening drum having interior, longitudinally extending webs forming inwardly opening pockets, and means to deliver stock to said pockets along a line at one side of and radially removed from the axis of the drum.

12. In a screening machine, a rotatable, foraminous screening drum having interior

perforate blades, and means to deliver stock to said blades along a line at one side of and radially removed from the axis of the drum.

13. In a screening machine, a rotatable, foraminous screening drum having interior, longitudinally extending perforate webs forming inwardly opening pockets, and means to deliver stock to said pockets along a line at one side of and radially removed from the axis of the drum.

14. In a screening machine, a rotatable, foraminous screening drum, a stock in-let pipe extending therein having a discharge mouth opening at one side of the vertical axis of the drum and extending throughout the length thereof.

15. In a screening machine, a rotatable, foraminous screening drum, a stock in-let pipe extending therein having a discharge mouth opening at one side of the vertical axis thereof, said discharge mouth having a weir-like lower edge over which stock is delivered to the descending side of the drum in sheet-like form.

16. In a screening machine, a rotatable, foraminous screening drum having interior blades, a stock in-let pipe extending therein at one side of the axis thereof, having a discharge mouth having a weir-like lower edge over which stock is delivered to said blades on the descending side of the drum in sheet-like form.

17. In a screening machine, a rotatable, foraminous screening drum having interior, longitudinally extending webs forming inwardly opening pockets, a stock in-let pipe extending therein at one side of the axis thereof, having a discharge mouth having a weir-like lower edge over which stock is delivered to said pockets on the descending side of the drum in sheet-like form.

18. In a screening machine, a rotatable, foraminous screening drum having interior perforate webs, a stock in-let pipe extending therein at one side of the axis thereof, having a discharge mouth having a weir-like lower edge over which stock is delivered to said blades on the descending side of the drum in sheet-like form.

19. In a screening machine, a rotatable, foraminous screening drum having interior, longitudinally extending, perforate webs forming inwardly opening pockets, a stock in-let pipe extending therein at one side of the axis thereof, having a discharge mouth having a weir-like lower edge over which stock is delivered to said pockets on the descending side of the drum in sheet-like form.

20. In a screening machine, in combination, screening means rotatable on journals slideable on their bearings, and means to rotate said screening means and to impart to it a reciprocating movement in the bearings; feeding means to deliver to said

screening means the material to be screened, and means to deliver from said screening means the material retained therein in the screening operation.

21. In a screening machine, in combination, a foraminous screening drum, means to feed stock to the interior of said drum, a gravity discharge for the residue of the screening operation, extending into said drum, and means to deliver said residue to said discharge.

22. In a screening machine, in combination, a foraminous screening drum, means to feed stock to the interior of said drum, a sloping discharge trough for the residue of the screening operation, extending into said drum, and means to deliver said residue to said trough.

23. In a screening machine, in combination, a rotatable, foraminous screening drum, interior, longitudinally extending blades on said drum, means to feed stock to the interior of said drum, and conveyer means extending into the drum and arranged to receive the residue of the screening operation from said blades.

24. In a screening machine, in combination, a rotatable, foraminous screening drum formed with interiorly opening pockets, means to feed stock to the interior of said drum, and conveyer means extending into the drum and arranged to receive the residue of the screening operation from said pockets.

25. In a screening machine, in combination, a rotatable, foraminous screening drum formed with interiorly opening pockets having perforate walls, means to feed stock to the interior of said drum, and conveyer means extending into the drum and arranged to receive the residue of the screening operation from said blades.

26. In a screening machine, in combination, a screening means having interior compartments, means to deliver stock to one of said compartments, and successively operating means to submerge the residue in said compartment and to discharge the re-screened residue.

27. In a screening machine, in combination, a movable screening means, means to feed stock to said screening means, means to agitate the unscreened residue, and means to carry away the residue after a further screening operation, the mentioned means acting successively during the movement of the screening means.

28. In a screening machine, in combination, a movable screening means, means to feed stock to said screening means, means to apply water to the screening means to agitate the unscreened residue, vanes to carry the residue, and conveyer means adapted to receive the rescreened residue from the vanes and discharge it from said screening means.

29. In a screening machine, in combination, a screening means, means to supply stock to said screening means in separated portions, and means to remove the unscreened residue of each portion from its part of the screening means before the supply of fresh stock thereto.

30. In a screening machine, in combination, a screening means having compartments, means to supply stock to the compartments, and means to remove the unscreened residue from each compartment before the supply of fresh stock thereto.

31. In a screening machine, in combination, stock supply means, separated screening devices arranged for successive presentation to said stock supply means in endless series, and means to remove the unscreened residue from each screening device before the supply of fresh stock thereto.

32. A foraminous screening drum of prismatic form having interior, longitudinal perforate blades.

33. A foraminous screening drum of prismatic form having interior, longitudinal perforate partitions forming inwardly opening pockets.

34. A foraminous screening drum of prismatic form having interior longitudinal perforate blades at the angles of the prism.

35. A foraminous screening drum of prismatic form having interior, longitudinal perforate partitions at the angles of the prism forming inwardly opening pockets.

36. In a screening machine, a rotatable, foraminous screening drum having the form of a frustum, the axis of the frustum being horizontal.

37. In a screening machine, a rotatable, foraminous screening drum having the form of a prismatic frustum, the axis of the frustum being horizontal.

38. In a screening machine, a rotatable, foraminous screening drum having the form of a double frustum, the larger bases of the parts being adjacent each other.

39. In a screening machine, a rotatable, foraminous screening drum having the form of a double prismatic frustum, the larger bases of the parts being adjacent each other.

40. In a screening machine, in combination, a foraminous screening drum, a foraminous drying drum having the form of a frustum, means to supply stock to the screening drum, and means to discharge the unscreened residue from the screening drum into the smaller end of the frustum.

41. In a screening machine, a screening drum, a drying drum, a supporting means common to both said drums and suspending them on either side thereof and a shaft about which said common supporting means is rotatable.

42. In a screening machine, a screening drum, a drying drum, a supporting means

common to both said drums, said means being the sole support of one of said drums and a shaft about which said common supporting means is rotatable.

43. In a screening machine, the combination with a tank of a polygonal screen cage revolvably mounted therein, a plurality of perforated, screening plates on the periphery thereof, radial partition walls between the screen plates, separating the cage into a series of compartments, a supply inlet for the stock and an exit for the screened stock communicating one with the exterior of the cage and the other with the interior thereof, means to rotate the cage to present said compartments in succession to the unscreened stock at a point above the level of the screened stock but to carry the stock in any compartment below the level of the body of screened stock, said partition walls being effective to lift the unscreened residue above the level of the screened stock, and means for maintaining a flow of water across the screening plates to wash the unscreened residue therefrom before the supply of fresh stock thereto.

44. A device of the character described comprising a tank, a screen cage revolvably mounted therein, partition walls separating the said cage into a plurality of compartments, provided each with a screening device, a supply inlet for the stock and an exit for the screened stock communicating one with the exterior of the cage and the other with the interior thereof, means to rotate the cage to present the said compartments in succession to the unscreened stock at a point above the level of the screened stock, means to rotate the cage to carry the stock in each compartment through the body of screened stock, said partition walls being effective to lift the unscreened residue above the level of the screened stock and the unscreened residue being removed from the screening device of each compartment before the supply of fresh stock thereto.

45. In a device of the character described, the combination with a tank, a screen cage revolvably mounted therein, partition walls separating the screening surface thereof into a plurality of units, a supply inlet for the stock and an exit for the screened stock, means to rotate the cage to present the said screening units in succession to the unscreened stock at a point above the level of the screened stock in the tank, means to rotate the cage to carry the stock in any one unit through the body of screened stock in the tank, said partition walls being effective to lift the unscreened residue on the screening unit above the level of the screened stock, and means to remove the unscreened residue from the surface of each screening unit before the supply of fresh, unscreened stock thereto.

46. A device of the character described, comprising a tank, a screen cage revolubly mounted therein, partition walls separating the screening surface into a plurality of units, a supply inlet for the stock and an exit for the screened stock, means to rotate the cage to present said screening units in succession to the screened stock at a point above the level of the screened stock in the tank, and means to remove the unscreened residue from the surface of each screening unit before the supply of fresh, unscreened stock thereto.

47. In a screening machine, in combination, a tank, stock supply means, a screened stock exit maintaining a body of screened stock in the tank, separated screening devices arranged for successive presentation to said stock supply means in endless series above the level of said screened stock, means to move said screening devices to carry the stock supply through said body of screened stock and then out of the same, and means to remove the unscreened residue from each screening device before the supply of fresh stock thereto.

48. In a screening machine, the combination of a polygonal screening drum, radial walls carried by said drum, and stock supply

means to supply stock to said radial walls and thereby impart a turning movement to the drum.

49. In a screening machine, in combination, a rotatable, foraminous screening drum, a stock inlet pipe located to deliver stock to the interior of the drum, means provided by the drum to receive the stock and impart through its delivery a turning movement to the drum.

50. In a pulp screen the combination of a rotatable screen drum, provision on the drum for receiving the stock and utilizing the head thereof to turn the drum, and a stock inlet for directing stock thereagainst.

51. In a pulp screen, the combination of a screen drum, radial blades therein, a stock inlet and means for utilizing the head of the stock against said blades to turn the drum.

52. In a pulp screen, the combination of a screen drum, a stock inlet, and means for utilizing the head of the stock to turn the drum.

In testimony whereof I, hereto affix my signature in presence of two witnesses.

ANTON J. HAUG.
